UNITED STATES PATENT OFFICE.

RAYMOND D. EMERY, OF WINCHENDON, MASSACHUSETTS, ASSIGNOR TO WILLIAM M. WHITNEY, OF WINCHENDON, MASSACHUSETTS.

INSTRUMENT FOR LAYING OUT THE CUTTING EDGES OF CUTTER-KNIVES.

1,302,645.

Specification of Letters Patent.

Patented May 6, 1919.

Application filed October 3, 1917. Serial No. 194,599.

To all whom it may concern:

Be it known that I, RAYMOND D. EMERY, a citizen of the United States, residing at Winchendon, county of Worcester, and State 5 of Massachusetts, have invented an Improvement in Instruments for Laying Out the Cutting Edges of Cutter-Knives, of which the following description, in connection with the accompanying drawings, is a specification 10 like characters on the drawings representing like parts.

The invention hereinafter described relates to instruments for laying out the cutting edges of knives of cutters for giving the 15 desired shape to moldings and other articles.

Such cutters usually comprise a body having a plurality of knives secured thereon adapted to act progressively on the molding stock to produce the desired contour thereon 20 when the stock is fed past the cutter. In order that these knives may efficiently cut the stock, it is customary to so mount them on the body of the cutter that the planes thereof will be oblique to the plane of the 25 stock when acting thereon. The arrangement of the knives with respect to the body of the cutter is such that the planes of the knives are tangent to a circle which is concentric to the axle of rotation of the body 30 of the cutter.

If the plane of each knife extended radially of the cutter, said plane would be perpendicular to the plane of the stock when the knife is attaining its greatest depth of 35 cut therein, and the contour of the cutting edge of the knife at such time would truly conform to the contour desired to produce on the molding. But when the knife is tilted from a plane perpendicular to the 40 stock, to a plane oblique to the stock, certain points on the knife edge will move toward the stock away from the axis of rotation of the cutter. Consequently, the contour of the oblique knife must differ from the contour 45 to be produced on the molding sufficiently to compensate for the change in position of said points.

I am aware that heretofore instruments have been devised for laying out the cutting 50 edges of knives to compensate for this obliquity, but they are objectionable for various reasons. Among others, they require an objectionably long time to operate; they require the exercise of great skill and care in 55 the use thereof; and even then inaccuracies are liable to occur.

By my invention, an instrument is provided which enables the cutting edges of knives for the purposes described to be quickly and easily laid out without error. 60

The invention may be best understood by the following description of one good form of instrument shown in the accompanying drawings, wherein:—

Fig. 1 is a side elevation of a rotary cutter showing the correct contour of the cutting edge of the knife, and showing the contour of a cross section of a piece of molding produced by said knife, the relation of the knife to the molding when making its 65 deepest cut being shown in dotted lines;

Fig. 2 is an end elevation of the cutter shown in Fig. 1, and a side elevation of the piece of molding shown therein, the position of the knife when making its deepest cut 70 being shown in dotted lines;

Fig. 3 is a face view of a knife showing the contour of the cutting edge thereof and a cross section through a piece of molding showing the contour thereof produced by 80 said knife, the knife being shown perpendicular to the plane of the molding to illustrate the difference between the contour of the knife and the contour of the molding;

Fig. 4 is an end elevation of the knife and 85 a side elevation of the piece of molding shown in Fig. 3; also showing the change in position of a point on the edge contour when the knife is in a position perpendicular to the molding as indicated in dotted lines; 90

Fig. 5 is a diagram to be referred to;

Fig. 6 is a perspective view of the instrument selected to illustrate the invention;

Fig. 7 on an enlarged scale shows the horizontal bar and the indicator means co-operating therewith;

Fig. 8 is an end elevation of the instrument showing the relation of the tracer means to the pattern and the knife blank; 95 and

Fig. 9 on an enlarged scale is a transverse section taken on line 9—9 of Fig. 7.

Referring to the drawings, a rotary cutter of usual construction, is shown in Figs. 1 and 2 mounted on a shaft 1 and comprises 105 a body 3 conveniently square in section, having knives 5 secured on two sides thereof by screw bolts 7. Each knife has a beveled edge 9 which has a contour for producing the desired contour on a piece of molding 11. 110

It will be noted that the contour of the knife is somewhat different from the con-

tour of the molding, but when the cutter is rotated to bring the knife in a position oblique to the plane of the molding, as indicated at 13, the contour of the knife exactly 5 conforms to the contour of the molding.

The difference between the contour of the cutting edge of the knife and the contour to be produced thereby on the molding, may be readily understood by reference to Fig. 10 3, in which the knife is shown rocked to a position perpendicular to the plane of the molding. When the knife is oblique to the plane of the molding as shown in Fig. 4, the points on the contour thereof will fit the 15 contour of the molding, but when rocked to its position shown in dotted lines in said figure, where it is perpendicular to the plane of the molding, certain points thereof will be elevated above the contour of the molding. 20 For example, when the knife is in its oblique position, the point *a* on the knife will engage the point *a'* on the molding, but when the cutter is rocked to its perpendicular position, this point will have moved to 25 the position indicated by *b*, and will have moved away from the molding a distance represented by *a'-b'* in Fig. 3.

To facilitate an understanding of the invention, reference may be had to the diagram shown in Fig. 5 wherein 15 designates a pattern of paper or other suitable material having a contour 16 of the desired design thereon, and supported a distance *x* from a knife blank 17, corresponding to the 30 distance between the axis of rotation 19 of the cutter and the plane of the knife. This distance will vary according to the size of cutter required. The pattern is also placed a distance *y* from said axis, corresponding 35 to the radial distance of the cutting edge of the knife from said axis. The pattern is in a plane containing the axis of rotation of the cutter, and the knife blank is in a plane tangent to a circle 20 concentric with the axis of the cutter. said posts at different elevations from the base.

Suitable means is provided for supporting the patterns 15, referred to. In the present instance of the invention, a table 35 is provided for this purpose mounted on and secured to an arm 37 projecting from one of the brackets 29, the construction being such, that the upper surface of the table is in a plane containing the axis of the bar 27, which corresponds to the axis 19 in the diagram, referred to. The pattern may be secured on the upper surface of the table by thumb tacks 39 or other suitable means. The contour of the pattern should be at a distance from the axis of the bar corresponding to the radial distance of the cutting edge of the knife from the axis of rotation of the cutter. In the present exemplification of the invention, this adjustment is obtained by elevating or lowering the pattern support and the horizontal bar, along the posts 25, but obviously instead of adjusting said parts, the knife blank table might be adjusted to accomplish this purpose.

The tracer means for laying out on the knife blank a contour suitable to produce the contour of the pattern, in the present instance of the invention, comprises an arm 49 which should be adjustable to vary the effective radial length thereof or distance between the contour of the pattern edge and the axis of said bar; and should be adapted to slide in the direction of the axis of said bar; and should be able to rock about said axis. To perform these functions, the arm, is mounted in a boss 51 on a stem 53 rising from a sleeve 55 adapted to slide along and rock on said bar. The arm may slide in the direction of the length thereof in said boss 51 and be frictionally held in different positions of extension by a spring-pressed plug 57 (Fig. 9) mounted in the stem 53 and adapted to engage a flat face 59 of said arm. The engagement of the plug with said face will also tend to prevent rotation of said arm in said boss.

A tracer or pin 61 may be mounted in a hole in the front end of said arm and be secured in different positions of adjustment by a screw 63 adapted to press split portions of said arm against said pin. A knob or handle 65 on said pin facilitates manipulation thereof.

The construction described is such that the tracer may be moved progressively along 10 the pattern and progressively along the knife blank to mark or lay out the desired contour thereon. In the present instance of the invention, the tracer is adjusted from point to point along the pattern equal increments and is shifted from each point to 15 lay out a corresponding point on the knife blank.

Suitable means may be provided for determining equal adjustments of the tracer 20 along the pattern and knife blank. To accomplish this, in the present instance of the invention, a pair of scales 67 and 69 (Figs. 6 and 7) are provided, one opposite the pattern support and the other opposite the 25 knife blank support. These scales are similar and each comprises a series of graduations conveniently on the horizontal bar 27 and marked with numbers to facilitate the reading thereof. A recess 71 in said sleeve 30 55 discloses the scales, and index lines 73 on the edges of said recess are adapted to be read in connection with the graduations of the scales.

In use, the pattern 15 is mounted on the 35 table 35 with its contour a distance from the axis of the horizontal bar 27 corresponding to the required distance between the cutting edge of the knife to be produced and the axis of rotation of the cutter. The knife 40 blank 17 is mounted on and secured to the table 41 in appropriate position. Then the thumb screws 33 are loosened to allow adjustment of the horizontal bar and pattern table along the post 25 to set the upper surface of said table a distance above the knife 45 blank corresponding to the distance required between the plane of the knife and the axis of rotation of the cutter, and the thumb screws are tightened to secure the table in 50 this position. Then the knob 65 of the tracer 61 is grasped to set the same at one end of the pattern contour, such, for example, the right end thereof (Fig. 6).

After the index line 73 is read in connection 55 with the scale 67, the tracer arm is moved along said bar to the left of Fig. 6 to a corresponding reading on the scale 69. It is then rocked downward to its position shown in dotted lines in Fig. 6, thereby 60 bringing the tracer into engagement with the knife blank to mark a point thereon. The tracer is then returned to its position above the pattern support and applied to the contour of the pattern at a point spaced 65 from the first point a selected increment.

The index 73 is read again in connection with the scale 67 and the tracer is adjusted along the horizontal bar to the left of Fig. 6 to a corresponding position on the scale 69. The tracer is then rocked downward to 70 mark a second point on the knife blank; and so on points may be taken progressively from the pattern and laid out on the knife blank until the complete contour is obtained.

The marginal portion of the knife blank between the contour thus laid out thereon, and the end of the blank adjacent thereto may be removed in a suitable grinding machine. Thus, a knife will be produced having a cutting edge with a contour compensating for the change therein from the contour of the pattern, made necessary by the obliquity of the plane of the knife with the plane of the molding when cutting thereon.

By the instrument described, it will be apparent that any pattern may be selected and the correct contour of a knife edge for reproducing the pattern on a knife blank may be quickly and easily obtained without 85 opportunity for error in laying out the same.

While the instrument has been described more particularly for laying out the contour of a knife edge of a cutter for shaping moldings, it will be understood that its 90 field of usefulness is not restricted thereto, but that it may be employed for laying out the contours of other articles.

It will be understood that the instrument disclosed herein is selected as one embodiment of the invention, and that various deviations may be made therefrom without departing from the spirit and scope of the appended claims.

What is claimed is:—

1. An instrument for laying out the cutting edges of knives of molding cutters and the like, comprising, in combination, a guide member, means to support a pattern a distance from the axis of said member determining the radial distance of the cutting edge of the cutter from the axis of the cutter head, means to support a knife blank a distance from the axis of said member determining the distance of the plane of the knife from the axis of the cutter head, and tracer means arranged to rock transversely about and slide axially of said member to lay out on said knife blank a contour determined by adjustments of said tracer means to progressive points on said pattern.

2. An instrument for laying out the cutting edges of knives of molding cutters and the like, comprising, in combination, a guide member having an axis corresponding to the axis of rotation of a cutter head, a pattern support having its upper surface in a plane containing said guide member axis, means to support a knife blank in a plane offset from said axis and pattern support, and tracer 125

- means constructed and arranged to swing about and move parallel to the axis of said member to lay out a contour on said knife blank determined by the distance of said pattern from said axis.
3. An instrument for laying out the cutting edges of knives for molding cutters and the like, comprising, in combination, a guide member having an axis corresponding to the axis of rotation of a cutter head, a support for a pattern having its upper surface in a plane containing said guide member axis, means to support a knife blank in a plane tangent to a circle concentric with said axis, and means mounted on said member adjustable to lay out a contour on said knife blank determined by the distance of said pattern from the axis of said member.
4. An instrument for laying out the cutting edges of knives of molding cutters and the like, comprising, in combination, a member having an axis corresponding to the axis of rotation of a cutter head, means to support a pattern, means to support a knife blank in a plane offset from said pattern, and tracer means movable to positions corresponding to the distances of points on the pattern from said axis, said tracer means being movable on said axis to lay out corresponding points on said knife blank.
5. An instrument for laying out the cutting edges of knives of molding cutters and the like, comprising, in combination, a bar having an axis corresponding to the axis of rotation of a cutter head, means to support a pattern in a plane containing said axis, means to support a knife blank in a plane tangent to a circle concentric with said axis, tracing means rotatively and slidably movable on said bar to project successive points from said pattern to said knife blank, and scales on said bar opposite said pattern and knife blank supports, for determining the extent of sliding movement of said tracer means in projecting the successive points.
6. An instrument for laying out the cutting edges of knives of molding cutters and the like, comprising, in combination, a guide member, a support for a pattern, a support for a knife blank, tracer means mounted to slide and rock on said guide member to project points progressively from the pattern to the knife blank, and means to effect equal increments of sliding movement of said tracer means along the pattern and knife blank.
7. An instrument for laying out the cutting edges of molding cutters and the like, comprising, in combination, a support, posts thereon, a guide bar connected to said posts having an axis corresponding to the axis of rotation of the body of a cutter, a table adapted to support a pattern mounted on said support and having its upper surface in the plane of said axis, a table adapted to support a knife blank in a plane tangent to a circle concentric with said axis, and tracer means mounted to slide along and rock on said bar to project points progressively from the pattern to the knife blank.
8. An instrument for laying out the cutting edges of knives of molding cutters and the like, comprising, in combination, a guide member having an axis corresponding to the axis of rotation of a cutter head, means to support a pattern, means to support a knife blank, means permitting relative adjustment of said guide member and knife blank supports to space them distances corresponding to the distances between the knife plane and axis of rotation of different sized cutters, and tracer means mounted to rock on and slide along the axis of said member to lay out on said knife blank an edge contour for reproducing said pattern.
9. An instrument for laying out the cutting edges of molding cutters and the like, comprising, in combination, a guide member having an axis corresponding to the axis of rotation of a cutter head, means to support a pattern, means to support a knife blank in a plane tangent to a circle concentric with said guide member axis, and means guided by said member movable along said pattern and blank to lay off a contour on the blank different from the contour of said pattern.
10. An instrument for laying out the cutting edges of molding cutters and the like, comprising, in combination, a support for a pattern, means to support a knife blank in a plane offset from the plane of the pattern, guiding means mounted adjacent said supports, and means mounted on said guiding means movable along the pattern and blank to lay off on said blank a contour for reproducing the contour of said pattern.
11. An instrument for laying out the cutting edges of molding cutters and the like, comprising, in combination, a guide member having an axis corresponding to the axis of rotation of a cutter head, means to support a pattern with its contour at distances from said axis varying according to the radius of the cutter, means to support a knife blank in a plane offset from said axis, said guide member and knife blank support being relatively adjustable to space the same according to the size of the cutter head, and means mounted on said guide member adjustable to said pattern contour and arranged to lay off a cutting edge contour on said knife blank suitable to reproduce said pattern on a piece of work when the knife is oblique to the plane of the work.
- In testimony whereof, I have signed my name to this specification.
- RAYMOND D. EMERY.
